UNITED STATES PATENT OFFICE.

ALMON ALMY, OF BELLEFONTAINE, OHIO.

OIL-BURNER.

1,265,867.

Specification of Letters Patent. Patented May 14, 1918.

Application filed May 31, 1917. Serial No. 172,012.

To all whom it may concern:

Be it known that I, ALMON ALMY, a citizen of the United States, residing at Bellefontaine, in the county of Logan and State of Ohio, have invented certain new and useful Improvements in Oil-Burners; and I do hereby declare the following to be a full, clear, and exact description of the invention, such as will enable others skilled in the art 10 to which it appertains to make and use the same.

The invention relates to improvements in oil burners.

The object of the present invention is to 15 provide a simple, practical and efficient oil burner of strong, durable and inexpensive construction designed for use in cooking stoves, heating stoves and various other places such as locomotives and the fire boxes 20 of various other furnaces where a burner of this type is desired and equipped with a generating burner adapted to supply the heat for converting into vapor or gaseous form liquid hydrocarbon for a plurality of 25 burners.

A further object of the invention is to 30 generate and supply gas which will burn the same as natural or artificial gas and which will be adapted to be mixed with air prior to entering the burner bodies and which will 35 burn with a blue flame and without fumes.

A further object of the invention is to 40 provide an oil burner equipped with a plurality of generating tubes having wicks adapted to prevent the liquid hydrocarbon 45 from flowing freely through the generating tubes in the form of a stream and which will force the liquid hydrocarbon in a thin sheet or body against the heating surfaces of the generating tubes.

The invention also has for its object to 45 provide an oil burner in which there will be perfect combustion and in which the generating tubes will be readily accessible to enable the wicks to be cleaned and maintained 50 free from carbon deposits.

With these and other objects in view, the 55 invention consists in the construction and novel combination of parts hereinafter fully described, illustrated in the accompanying drawings and pointed out in the claims here-to appended; it being understood that various changes in the form, proportion, size and minor details of construction, within 60 the scope of the claims, may be resorted to without departing from the spirit or sacri-

ficing any of the advantages of the invention.

In the drawings:

Figure 1 is a plan view of an oil burner 60 constructed in accordance with this invention.

Fig. 2 is a front elevation of the same partly in section, the cylindrical casing being in section. 65

Fig. 3 is a side elevation of the oil burner, illustrating the arrangement of the same with relation to the stove. 70

Fig. 4 is a detail sectional view on the line 4—4 of Fig. 2 illustrating the construction of the generating burner. 75

Fig. 5 is an enlarged detail sectional view of one of the generating tubes.

Fig. 6 is a reverse plan view of the generating burner. 75

Fig. 7 is a detail sectional view illustrating the construction of the needle valve for controlling the flow of oil to the generating tubes.

Fig. 8 is a detail sectional view of the outlet of the generating tube and the inlet of the mixing tube. 80

Like numerals of reference designate corresponding parts in the several figures of the drawings. 85

In the accompanying drawings, in which is illustrated the preferred embodiment of the invention, 1 designates a generating burner consisting of a hollow cylindrical body having a perforated top 2 and designed to be constructed of cast metal or other suitable material and having mounted upon it a vertical cylindrical casing 3, in which is located generating tubes 4 and 5. The vertical cylindrical casing, which may be constructed of heavy sheet metal or other suitable material, is fitted around the top of the generating burner preferably in a recess 7 thereof, and it may be secured to the generating burner or simply fitted around the same. 95

The upper end of the cylindrical casing is located beneath the lid receiving opening 8 of the stove 9. While the burner is shown arranged in a cooking stove 9 of the ordinary construction, it may of course be employed in various places where heat of a maximum degree is desired. 105

The generating tubes 4 and 5, which are provided with detachable inverted U-shaped sections 10, are designed to be constructed of cast iron or other suitable material and 110

the said sections 10, which are connected with the inlet and outlet portions 11 and 12 of the generating tubes by suitable couplings or unions 13, are provided with removable wicks 14 preferably constructed of asbestos, mineral wool or other similar absorbent material and adapted to prevent the liquid hydrocarbon from flowing through the generating tubes in a stream and capable of spreading the liquid hydrocarbon and causing the same to contact with the heating surfaces of the generating tubes in a thin sheet. This will enable the gas or vapor to be generated from the liquid hydrocarbon with sufficient rapidity and volume to supply the burners with the necessary amount of gas. The couplings or unions 13 enable the inverted U-shaped section 10 to be readily detached when it is necessary to remove the wick for cleaning or renewing the same and for removing any carbon deposits within the generator tubes. The inlet portions 11 of the generating tubes are connected by pipes 15 with a supply tube or tubular member 16 having a plurality of needle valves 17 corresponding with and controlling the flow of liquid hydrocarbon into the pipes 15. The supply tube or needle valve casing 16 is connected by a supply pipe 18 with a tank 19, from which hydrocarbon is preferably fed by pneumatic pressure, any ordinary air compressor being adapted to be connected with the tank for supplying the compressed air to the same. The stem or member of each needle valve is mounted in a sleeve 20 and it extends through the supply tube or casing 16 at one side of the same and co-operates with a valve seat 21 at the opposite side of the same. The valve seat 21 may be formed in the end of the pipe 15 or in any other suitable manner, as will be readily understood. By this arrangement of needle valves, the flow of liquid fuel to any one of the burners may be controlled, and one or more of the burners of a stove may be operated.

The generating tubes 4 and 5 are connected with mixing tubes 22 and 23, which are connected respectively with the generating burner 1 and plain or ordinary burners 24. The mixing tubes are provided with upturned terminal portions 25 and 26, which are preferably threaded into the bottoms of the burners 1 and 24. The outlet portions 12, of the generating tubes, are provided with jet apertures 27 which are arranged to discharge in the mixing tubes, and each of the mixing tubes is provided with laterally extending air inlet arms or extensions 28 of cylindrical form, but any other desired form of arm or extension may of course be employed. The mixing tubes are preferably horizontally arranged and the jet apertures of the outlet portions of the generating tubes are located opposite the mixing tubes and the

gas is discharged, under pressure, from the generating tubes into the mixing tubes and cause the air to flow into the laterally extending arms 28 and mix with the gas entering the mixing tubes. The mixture burns with a blue flame without fumes and with perfect combustion, producing a maximum amount of heat from a given quantity of fuel. The burners 24 may be of any desired construction, but they are shown in the accompanying drawings as hollow cylindrical formation similar to the burner 1 and provided with perforated top walls. The generating tubes 5 may be of any desired number, and one or more of the burners may of course be employed, and the said mixing tubes 23 are shown in the accompanying drawings as located at opposite sides of the generating burner and supported by arms 29 which are located exteriorly of the cylindrical casing 3 which is provided with suitable slots 30 to permit it to be readily placed over the generating tubes and removed when required. The jet apertures are preferably formed in caps 31 threaded on to the outlet ends of the generating tubes and extending into the mixing tubes at the inner ends of the laterally projecting arms.

The mixing tube 22 is located below the generating burner and the main or ordinary burners are provided with openings 32 formed in the bottoms of the main or ordinary burners and arranged eccentrically and adapted to permit a rotary movement of the burner 24 to arrange the latter in different positions to accommodate the openings of stoves of different sizes and different arrangement of stove lids. By this adjustment the main or ordinary burners may be arranged at different distances from the generating burner.

The burner is started by a torch 33 preferably constructed of asbestos or similar absorbent material and provided with a suitable stem 34 and adapted to be saturated with denatured alcohol or other suitable liquid for supplying the heat necessary to generate gas in the generating tube 4 that is connected with the generating burner. The torch is preferably U-shaped, as shown, to enable it to embrace the generating tube and when sufficient heat has been developed in the cylindrical casing to operate the generating tube 4, the gas will be generated and the torch will ignite the generating burner after which the torch may be readily removed and the burner will supply the necessary heat for the generation of gas in all of the tubes 4 and 5.

What is claimed is:

1. An oil burner including a generating burner, a generating tube extending through and located above the burner so as to be heated by the same and provided with an outlet, a mixing tube connected with the

- generating burner and having the outlet of the generating tube discharging into it, said mixing tube being provided with an air inlet arm or extension located at the said outlet.
- 5 2. An oil burner of the class described including a generating burner, a generating tube having a detachable approximately inverted U-shaped portion having end couplings and located above the generating burner and provided therein with a removable wick of absorbent material, said generating tube having an outlet, and a mixing tube connected with the generating burner and receiving the outlet of the generating tube, said mixing tube being provided with an air inlet for mixing air with the gas before the gas is burned by the generating burner.
- 10 3. An oil burner of the class described including a generating burner, a generating tube piercing the burner and provided with an approximately inverted U-shaped portion located above the generating burner, said generating tube being also provided at one side of the burner with an outlet located below the burner, and a mixing tube receiving the said outlet and connected with the generating burner and having an air inlet located at the outlet.
- 15 4. An oil burner of the class described including a generating burner, a mixing tube connected with the generating burner at the bottom thereof and provided with laterally extending air inlet arms open at their outer ends, and a generating tube extending through the generating burner and having an approximately U-shaped portion located above the same, said generating tube extending downwardly below the generating burner and having an outlet extending into the mixing tube at the inner ends of the said arms.
- 20 5. An oil burner of the class described including a generating burner, mixing tubes located at opposite sides of the burner and having laterally extending air inlet arms open at their outer ends, generating tubes having approximately U-shaped portions located above the generating burner and provided with outlets extending into the said mixing tubes, and burners connected with the mixing tubes.
- 25 6. An oil burner of the class described including a generating burner, mixing tubes located at opposite sides of the burner and having laterally extending air inlet arms open at their outer ends, generating tubes having approximately U-shaped portions located above the generating burner and provided with outlets extending into the said mixing tubes, burners connected with the mixing tubes, a lower mixing tube connected with the generating burner, and a generating tube discharging into the lower mixing tube and having an approximately U-shaped portion located above the generating burner.
- 30 7. An oil burner of the class described including a generating burner, mixing tubes located at opposite sides of the burner and having laterally extending air inlet arms open at their outer ends, generating tubes having approximately U-shaped portions located above the generating burner and provided with outlets extending into the said mixing tubes, burners connected with the mixing tubes, a lower mixing tube connected with the generating burner, a generating tube discharging into the lower mixing tube and having an approximately U-shaped portion located above the generating burner,
- 35 8. An oil burner of the class described including a generating burner, a lower mixing tube connected with the generating burner, upper mixing tubes mounted upon the burner at opposite sides thereof and having supporting arms rigid with the generating burner, said mixing tubes being provided with air inlet arms, generating tubes piercing the generating burner and having approximately U-shaped portions located above the generating burner, said generating tubes having outlets connected with the mixing tubes, supply pipes connected with the generating tubes, a needle valve casing connected with the supply pipes and provided with a plurality of needle valves for controlling the flow of oil into the said pipes, and an oil supply connected with the needle valve casing.
- 40 9. An oil burner of the class described including a generating burner, mixing tubes located at opposite sides of the burner and having laterally extending air inlet arms open at their outer ends, generating tubes having approximately U-shaped portions located above the generating burner and provided with outlets extending into the said mixing tubes, burners connected with the mixing tubes, a lower mixing tube connected with the generating burner, a generating tube discharging into the lower mixing tube and having an approximately U-shaped portion located above the generating burner.
- 45 10. An oil burner of the class described including a generating burner, mixing tubes located at opposite sides of the burner and having laterally extending air inlet arms open at their outer ends, generating tubes having approximately U-shaped portions located above the generating burner and provided with outlets extending into the said mixing tubes, burners connected with the mixing tubes, a lower mixing tube connected with the generating burner, a generating tube discharging into the lower mixing tube and having an approximately U-shaped portion located above the generating burner.
- 50 11. An oil burner of the class described including a generating burner, mixing tubes located at opposite sides of the burner and having laterally extending air inlet arms open at their outer ends, generating tubes having approximately U-shaped portions located above the generating burner and provided with outlets extending into the said mixing tubes, burners connected with the mixing tubes, a lower mixing tube connected with the generating burner, a generating tube discharging into the lower mixing tube and having an approximately U-shaped portion located above the generating burner.
- 55 12. An oil burner of the class described including a generating burner, mixing tubes located at opposite sides of the burner and having laterally extending air inlet arms open at their outer ends, generating tubes having approximately U-shaped portions located above the generating burner and provided with outlets extending into the said mixing tubes, burners connected with the mixing tubes, a lower mixing tube connected with the generating burner, a generating tube discharging into the lower mixing tube and having an approximately U-shaped portion located above the generating burner.

In testimony whereof I affix my signature in presence of two witnesses.

ALMON ALMY.
